UNITED STATES PATENT OFFICE.

FERNAN O. CONILL, OF MARSEILLE, FRANCE.

REFRIGERATING APPARATUS.

Application filed November 1, 1921. Serial No. 512,081.

To all whom it may concern:

Be it known that I, FERNAN O. CONILL, a citizen of the Republic of Cuba, and a resident of Marseille, France, have invented 5
5 a certain new and useful Refrigerating Apparatus, of which the following is a specification.

This invention relates to refrigeration and more particularly to refrigerating apparatus. 10

One of the objects of this invention is to provide a simple and practical refrigerating apparatus of thoroughly reliable and dependable action and of a construction and 15 form as will be readily portable. Another object is to provide a simple and practical means for reliably controlling the action of the apparatus, which apparatus may be in general of the type set forth in my co-pending application, Serial No. 496,232, filed 20 August 29, 1921. Another object is to provide a valve mechanism for controlling the action of such apparatus, which mechanism will be of simple construction, thus lending 25 itself to inexpensive manufacture and to ready and convenient manual control. Other objects will be in part obvious or in part pointed out hereinafter.

The invention accordingly consists in the 30 features of construction, combinations of elements and arrangements of parts as will be exemplified in the structure to be hereinafter set forth, and the scope of the application of which will be indicated in the 35 following claims.

In the accompanying drawing, in which is shown one of various possible embodiments of this invention:—

Figure 1 is a sectional view of this apparatus showing the same tilted in one direction. 40

Figure 2 is a similar view partly in elevation showing the same tilted in the opposite direction.

Referring now to the drawing and more particularly to Fig. 1, there is shown a receptacle or container 1 adapted to receive a suitable liquid in which is dissolved a suitable liquefiable gas. Thus, for example, the 45 solvent may comprise water, glycerine, or a suitable heavy oil, and the gas dissolved therein may be ammonia or sulphur dioxide, for example. For convenience of descrip-

tion, it will be hereinafter assumed that water is used for the solvent liquid and 55 ammonia for the gas adapted to be dissolved therein.

The apparatus also includes a refrigerating and a condensing chamber 2, the latter being connected to the receptacle 1 as by 60 a conduit 3, this conduit being preferably rigid and also rigidly connected to each of the receptacles in about the relation shown in the drawing. The conduit 3 has a downwardly directed branch or leg 4 connecting 65 to the interior of the refrigerating chamber 2, the latter being provided with an interior chamber 5 preferably of tapered form as shown in the drawing. In this chamber 5 may be placed directly the substances desired to be refrigerated or frozen but preferably the chamber 5 receives suitable molds or auxiliary containers in which the substances to be frozen are placed as is more clearly set forth in my above-mentioned co- 70 pending application. 75

The conduit 3 has a downwardly extending branch 6 adjacent its other end whence it is formed to provide two branches 7 and 8 each communicating with the receptacle 1, the former being in communication with the receptacle 1 adjacent its upper end and the latter being extended downwardly toward the bottom of the receptacle 1 and well below the normal level of the liquid 85 contained therein. The connection between the branch 6 of the conduit 3 and the branches 7 and 8 is preferably made by means of a yoke portion 6^a extending transversely of the branch 6 and in a general horizontal 90 direction as shown in the drawing. The branches 7 and 8 are provided with valve seats 9 and 10, respectively, and preferably at their upper ends and substantially where they join the yoke portion 6^a. The valve 95 seats 9 and 10 are adapted to coact with a valve member preferably taking the form of a hollow ball 12. The bottom portion of the connecting yoke 6^a is preferably curved so as to provide a portion intermediate its 100 ends of higher level than the valve seats 9 or 10 and so that there is in effect formed a roll-way for the ball valve 12, this roll-way 11 acting to guide the ball valve 12 in its transit from one valve seat to the 105 other. Thus, referring to Fig. 1, it will be

noted that when the apparatus is tilted into the position shown in Fig. 1, the ball valve 12 rides into and remains in connection with the valve seat 9. Vice versa, when the apparatus is tilted in the opposite direction or into the position shown in Fig. 2, the ball valve 12 rolls across the way 11 and into coacting position with respect to the valve seat 10.

- 10 In order to insure the proper positioning of the valve 12 with respect to the valve seats there are provided two handles 13 and 14 conveniently secured to the transversely extending conduit 3, it being noted that the handles 13 and 14 are arranged on opposite sides of what may be termed the center of gravity of the apparatus as a whole. By lifting the apparatus by the handle 13, the apparatus is automatically swung into the position shown in Fig. 1 and the ball valve 12 placed in co-action with the valve seat 9.

When the apparatus is grasped by the handle 14 it is automatically swung into the position shown in Fig. 2 in which it will be noted that the valve 12 is transferred to the valve seat 10 in the branch 8 and has thus in effect opened the passage through the branch 7. In this position the apparatus is in readiness to begin its operation. Heat is applied to the receptacle 1 in any suitable manner and as the heating progresses the gas, such as ammonia, is driven out of the solvent, such as water for example, and passes through the branch 7, the branch 6, the conduit 3, the branch 4 and into the refrigerating receptacle 2. During this stage the receptacle 2 may be cooled as by dousing it with, or immersing it in, water or any other suitable cooling medium, and the gas transferred as above described to the refrigerating receptacle 2 condenses and in effect liquefies. After substantially all of the gas has been driven out of the solvent in the receptacle 1 the heating of the solvent is discontinued and the apparatus is thereupon grasped by the handle 13 thereby automatically to position the parts as shown in Fig. 1.

When so positioned, the receptacle 1 may be cooled as was the receptacle 2 during the stage hereinabove described, and the substance to be frozen having been placed within the chamber 5 undergoes cooling or refrigeration. The liquefied gas collects in the lower annular space in the refrigerating chamber 2, which space, it will be noted, surrounds the interior chamber 5 and hence the substances to be frozen, and the liquefied gas begins to evaporate. As it evaporates it obtains its heat of evaporation from the contents of the chamber 5, thus cooling the contents, and upon continued evaporation passes upwardly through the branch 4, thence through conduit 3, branch 6 and branch 8 into the receptacle 1, it being noted

that the ball valve 12 prevents the passage of the gas through the branch 7 which, as above noted, communicates with the upper portion of the receptacle 1. The gas is thus constrained to flow downwardly through the extended branch 8 and into the solvent, whence it is reabsorbed thereby and again passes into solution, it being noted that the cooling of the receptacle 1 during this stage assists in facilitating the reabsorption of the gas by the solvent. The apparatus may be operated through the above cycles as often as desired, it being noted that no loss of solvent or gas takes place.

It will thus be seen that there has been provided in this invention an apparatus in which the several objects hereinabove set forth as well as many advantages are achieved. The construction, it will be noted, is simple and yet thoroughly practical and reliable and thus insures proper sequential operation of the apparatus through its various cycles.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

What I claim is:

1. In apparatus of the character described, in combination, a receptacle adapted to receive a liquid having dissolved therein a liquefiable gas, a refrigerating chamber adapted to receive and have condensed therein the gas driven out of solution with said liquid in said first receptacle upon the heating of the latter, a conduit connecting said two receptacles to permit passage of the gas from one to the other, said conduit having branches communicating with said first receptacle, one branch communicating with the upper portion of the receptacle and the other communicating therewith at a point adjacent the bottom thereof, and means adapted upon the tilting of the apparatus in one direction or the other to open one of said branches and close the other.

2. In apparatus of the character described, in combination, a receptacle adapted to receive a liquid having dissolved therein a liquefiable gas, a refrigerating receptacle adapted to receive and have condensed therein the gas driven out of solution with the liquid in said first receptacle upon the heating of the latter, a conduit connecting said two receptacles and adapted to conduct the gas from one receptacle to the other, said conduit having a port communicating with the upper portion of said first receptacle and another port communicating with said first receptacle at a point adjacent the bottom thereof, and a single valve associated with

said ports and adapted upon a tilting of the first receptacle to close one port and open the other.

3. In apparatus of the character described, in combination, a receptacle adapted to receive a liquid having dissolved therein a liquefiable gas, a refrigerating receptacle adapted to receive and have condensed therein the gas driven out of solution with the liquid in said first receptacle upon the heating of the latter, a conduit connecting said two receptacles and adapted to conduct the gas from one receptacle to the other, said conduit having a port communicating with the upper portion of said first receptacle and another port communicating with said first receptacle at a point adjacent the bottom thereof, and a ball valve associated with said ports and adapted upon tilting of said first receptacle to close one of said ports and open the other.

4. In apparatus of the character described, in combination, a receptacle adapted to receive a liquid having a liquefiable gas dissolved therein, a second receptacle adapted to receive and have condensed therein the gas driven out of said liquid in said first receptacle upon the heating of the latter, a rigid conduit rigidly connecting said two receptacles and adapted to conduct the gas from one to the other, said conduit connecting with said first receptacle through two ports, one of which is in communication with the upper portion of said first receptacle and the other of which is in communication with said first receptacle at a point adjacent the bottom thereof, means adapted upon tilting of the apparatus in one direction or the other to open one of said ports and to close the other, and a pair of handles associated in spaced relation with said apparatus and one on each side of the center of gravity of the apparatus whereby lifting of the apparatus by one handle tilts the apparatus in one direction and lifting of the apparatus by the other handle tilts the apparatus in the opposite direction.

5. In apparatus of the character described, in combination, a receptacle adapted to receive a liquid having a liquefiable gas dissolved therein, a second receptacle adapted to receive and have condensed therein the gas driven out of said liquid in said first receptacle upon the heating of the latter, a rigid conduit rigidly connecting said two receptacles and adapted to conduct the gas from one to the other, said conduit connecting with said first receptacle through two ports, one of which is in communication with the upper portion of said first receptacle and the other of which is in communication with said first receptacle at a point adjacent the bottom thereof, a valve coacting with said two ports and adapted upon tilting of the apparatus to open one port

and close the other, and a pair of handles associated with the apparatus and positioned on opposite sides of the line of gravitation thereof whereby lifting the apparatus by one handle tilts the apparatus in one direction to effect opening of one port and closing of the other, and lifting the apparatus by the other handle tilts the same in the opposite direction to effect a reverse actuation of said valve.

6. In apparatus of the character described, in combination, a receptacle adapted to receive a liquid having dissolved therein a liquefiable gas, a second receptacle adapted to receive and have condensed therein the gas driven out of solution with the liquid in said first receptacle upon the heating of the latter, a conduit for connecting said two receptacles to permit the transfer of gas from one to the other, a pair of ports communicating on one side thereof with one end of said conduit and communicating at the other side thereof, respectively, with the upper portion of said first receptacle and with the bottom portion of said first receptacle, a single ball valve coacting with said ports, and means forming a runway between said two ports adapted upon tilting of said first receptacle to transfer said ball member from one port to the other.

7. In apparatus of the character described, in combination, a receptacle adapted to receive a liquid having dissolved therein a liquefiable gas, a second receptacle adapted to receive and have condensed therein the gas driven out of solution with said liquid in said first receptacle upon the heating of the latter, means forming a communication between said two receptacles to permit the passage of gas from one to the other and including two passages, one in communication with the upper portion of said first receptacle and the other in communication with the bottom portion of said first receptacle, and means adapted upon a tilting of the apparatus in one direction or the other to open one of said passages and close the other.

8. In apparatus of the character described, in combination, a receptacle adapted to receive a liquid having dissolved therein a liquefiable gas, a second receptacle adapted to receive and have condensed therein the gas driven out of solution with said liquid in the first receptacle upon the heating of the latter, means forming a communication between said two receptacles for permitting the passage of gas from one to the other, said means including a pair of passages, one in communication with the upper portion of said first receptacle and the other in communication with the bottom portion of said first receptacle, a substantially horizontally extending conduit connecting said two passages and in communication with said second receptacle, valve seats at the upper ends

of said two passages and adjacent their point of connection with said horizontally extending conduit, and a rolling valve coacting with said valve seats and adapted alternately to be seated upon one or the other of said valve seats in accordance with the direction in which the apparatus is tilted, said horizontally extending conduit connect-

ing said two passages acting as a roll-way for guiding said rolling valve from one 10 valve seat to the other.

In testimony whereof, I have hereunto signed my name, at New York, in the county of New York, and State of New York, this 14th day of October, 1921.

FERNAN O. CONILL.
